(57) **CLAIM**

The ornamental design for a panel for ceiling, as shown and described.

DESCRIPTION

FIG. 1 is a perspective view of a panel for ceiling according to the present design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged detail of the circumscribed area "8" in FIG. 1.

The outlined shapes on the front surface of the ceiling panel are rounded recesses. FIG. 8 shows the outlined shapes in detail.

1 Claim, 5 Drawing Sheets
